Primary Examiner — Patricia A Palasik

(57) **CLAIM**

The ornamental design for a transfer robot, as shown and described.

DESCRIPTION

1. Transfer robot
  - 1.1: Front, left perspective view;
  - 1.2: Front, left perspective view;
  - 1.3: Front elevation view;
  - 1.4: Back elevation view;
  - 1.5: Left side elevation view;
  - 1.6: Right side elevation view;
  - 1.7: Top plan view;
  - 1.8: Enlarged view of the portion shown in rectangle 1.8 in Fig. 1.1.
1. The broken lines shown in the figures depict portions of the transfer robot that form no part of the claimed design; The dot-dash broken lines in fig. 1.1, 1.8 and the label "1.8" in fig. 1.1 are for the purpose of depicting the cut line of the enlarged view and form no part of the claim. 2. The bottom view is omitted since the bottom of the product is hardly seen in use.

1 Claim, 8 Drawing Sheets(56)
